UNITED STATES PATENT OFFICE.

WARREN C. LEINBACH, OF WILKINSBURG, PENNSYLVANIA.

PICKLING MACHINE.

1,415,589.

Specification of Letters Patent.

Patented May 9, 1922.

Application filed March 26, 1921. Serial No. 455,770.

To all whom it may concern:

Be it known that I, WARREN C. LEINBACH, a citizen of the United States, and a resident of Wilkinsburg, in the county of Allegheny and State of Pennsylvania, have invented a new and useful Improvement in Pickling Machines, of which the following is a specification.

The invention relates to that type of pickling machines which include a plurality of vats and mechanism for reciprocating the articles being treated in the vats, and for placing the articles in and removing them from the vats.

15 The object of the invention is to provide a pickling machine of the general character explained which will be simple in construction, effective in operation and economical to manufacture. A further object of the 20 invention is to provide a pickling machine in which the reciprocation of the articles being treated in the vats and the removal of the articles from the vats is effected by independent motors and driving connections 25 of simple design.

The invention is illustrated in the accompanying sheets of drawings, of which Fig. 1 is a combined elevation and vertical central sectional view of the complete apparatus; 30 Figs. 2, 3 and 4 horizontal sectional views to enlarged scale taken, respectively, on the lines II-II, III-III and IV-IV, Fig. 1; and Fig. 5 a side view of an intermediate portion of the ram, the plane of view being 35 indicated by the line V-V, Fig. 1.

In pickling machines of the character contemplated herein, three pickling vats 1, are usually arranged at quarter points around a vertically movable ram 2. Two of 40 such vats are indicated in Fig. 1, the position of the third usually being immediately back of the ram. The fourth quarter point is usually used for a loading and unloading station.

45 In the practice of the invention, the ram 2 is preferably formed of an H-section, the lower end of which extends into a well 3 below the floor level 5. At the upper end of the ram there are a plurality of laterally extending arms 6, from the outer ends of which cages 7 are suspended by means of rods or cables 8. The arms 6, of which there are preferably four in number, form a spider having a central hub 9 rotatably mounted on a cap 10 secured to the top of the ram. Preferably, a race of ball bear-

ings 11 is arranged between the cap 10 and hub 9. By this construction, the spider may be readily rotated upon the top of the ram to move the cages from one station to another when the ram is in such position as to support the cages above the tops of the vats.

While the cages are in the vat in the positions indicated in Fig. 1, they are vertically reciprocated to circulate the acid bath, water or other treating liquid in the vats and upon the faces of the articles. For this purpose, an arm 12 is pivoted, preferably at its outer end to a lug 13 formed on a frame 14. The inner end of the arm engages the ram, and means are provided for oscillating the arm to reciprocate the ram. The engagement of the ram by arm 12 is preferably effected by a pair of links 15 pivoted to the outer end of the arm, a collar 16 surrounding the ram and connected to the outer ends of the links, and a pair of brackets 17 attached one to each side of the web of the ram 2 and projecting laterally therefrom. The collar 16 bears upon the lower faces of brackets 17, so that, when the collar is reciprocated, the ram will move upwardly and downwardly. However, the connection is such that the ram 2 may be moved upwardly independently of the movement of collar 16, as will presently be explained.

For reciprocating arm 12, an electric motor 18 may be mounted upon the base of frame 14, and suitable driving connections arranged between the motor and arm. In the illustrated embodiment of the invention, the driving connections include a pinion 19 connected to the armature shaft and meshing with a pinion 20 mounted on a rotatable crank shaft 21, to which there is attached a pitman 22 pivotally connected as at 23 to arm 12. By such connections, the continuous rotation of the motor effects a continuous oscillation of the arm, which in turn causes continuous reciprocation of the ram.

The vertical movement of the ram 2 to remove the cages from the vats is preferably effected by a separate motor and suitable driving connections between it and the ram. 105 The motor for this purpose may be an electric motor 24 mounted on the base of frame 14. To the armature shaft of the motor, there is connected a pinion 25 which drives a pinion 26 secured to a rotary shaft 27 provided with a pair of sprocket wheels 28 arranged one on each side of ram 2. Around

each sprocket wheel there is a chain 29, the lower end of which is attached to a base 30 at the lower end of the ram. By operating the motor 24, the sprocket wheels 28 may be 5 rotated to either elevate or lower ram 2. The free end of chains 29 may pass around rollers 31, arranged in well 3, as seen in Fig. 1.

To hold the ram in its vertical position, 10 suitable guides are provided. To avoid friction, such guides may take the form of a pair of oppositely disposed rollers 32 mounted on the top of frame 14, a roller 33 mounted on rotary shaft 27, and a roller 34 arranged in the upper end of well 3 in a position substantially opposite to the roller 33.

In the operation of the pickling machine, assuming that the cages have been filled with material to be treated and that the apparatus is in the position indicated in Fig. 1, motor 18 may be operated to cause the ram 2 to reciprocate. The driving connections from the motor include pinions 19 and 20, crank shaft 21, pitman 22, pivoted arm 12, links 15, collar 16 and brackets 17. At the end of a pickling operation, the motor 18 may be stopped and motor 24 operated to elevate the ram 2 to such position that the lower edges of the cages are above the 25 upper edges of the vats. The driving connections for this purpose include pinions 25 and 26, rotary shaft 27, sprocket wheels 28, chains 29 and a base 30 upon which the ram rests. When the ram has been elevated to 30 the proper position, the cages may be engaged by hand and pulled so as to cause the spider to rotate upon the upper end of ram 2. The ram may then be lowered by using motor 24 as a brake, after which motor 18 35 may be again started in operation to reciprocate the ram.

According to the provisions of the patent statutes, I have described the principle and operation of my invention, together with the 45 construction which I now consider to represent the best embodiment thereof. However, I desire to have it understood that, within the scope of the appended claims, the invention may be practiced by other forms 50 of construction than that specifically shown and described.

I claim:

1. In a pickling machine, the combination with a plurality of vats, of a vertically movable ram provided with lateral arms having cages suspended therefrom, a pivoted arm engaging to said ram, a motor, and connections between said motor and arm for oscillating the arm to reciprocate the ram.

2. In a pickling machine, the combination with a plurality of vats, of a vertically movable ram provided with lateral arms having cages suspended therefrom, a frame, a horizontally disposed arm pivoted to the frame, a link pivoted to said arm and pro-

vided with an abutment engaging said ram, a motor, and connections between said motor and arm for oscillating the arm to reciprocate the ram.

3. In a pickling machine, the combination with a plurality of vats, of a vertically movable ram provided with lateral arms having cages suspended therefrom and provided further with a laterally extending bracket, a frame, a horizontally disposed arm pivoted at one end of said frame, a link pivotally connected to the other end of said arm and provided with an abutment adapted to engage said bracket, a motor, and connections between said motor and arm for oscillating the arm to reciprocate the ram.

4. In a pickling machine, a combination with a plurality of vats, of a vertically movable ram provided with lateral arms having cages suspended therefrom and further provided with a pair of laterally extending brackets, a frame, a horizontally disposed arm pivoted at one end of the frame, a pair of links pivoted to the other end of said arm and provided with a collar surrounding said ram and engaging said brackets thereon, a motor, and connections between said motor and arm for oscillating the arm to reciprocate the ram.

5. In a pickling machine, the combination with a plurality of vats, of a vertically movable ram provided with lateral arms having cages suspended therefrom, a frame, a horizontally disposed arm pivoted to the frame, connections between said arm and ram, a motor, a rotary crank shaft driven by said motor, and a pitman between said shaft and arm for oscillating the arm to reciprocate the ram.

6. In a pickling machine, the combination with a plurality of vats, of a vertically movable ram provided with lateral arms having cages suspended therefrom, a pivoted arm connected to said ram, a motor, connections between said motor and arm for oscillating the arm to reciprocate the ram, and independent means for moving the ram upwardly to remove the cages from the vats.

7. In a pickling machine, the combination with a plurality of vats, of a vertically movable ram provided with lateral arms having cages suspended therefrom, a pivoted arm connected to said ram, a motor, connections between said motor and arm for oscillating the arm to reciprocate the ram, a second motor, and connections between the second motor and ram for moving the latter upwardly to remove the cages from the vats.

8. In a pickling machine, the combination with a plurality of vats, of a vertically movable ram provided with lateral arms having cages suspended therefrom, means for reciprocating said ram to cause the cages to move upwardly and downwardly in the vats, a motor, a rotary shaft driven by said motor

and provided with a pair of sprocket wheels arranged one at each side of said ram, chains engaged by said sprockets and connected at their ends to said ram whereby the 5 ram may be moved upwardly to remove the cages from the vats.

9. In a pickling machine, the combination with a plurality of vats, of a vertically movable ram provided at its upper end with 10 lateral arms having cages suspended therefrom and further provided intermediate of its ends with a pair of oppositely disposed lateral brackets, a frame surrounding said ram and provided with guide rollers for 15 maintaining the ram in vertical position, a horizontally disposed arm pivoted at one end to said frame, a pair of links pivotally connected to the other end of said arm, a collar attached to the outer ends of said 20 links and adapted to bear upon said brackets, a motor, a crank shaft driven by said motor, a pitman connecting said crank shaft with said arm for oscillating the arm to reciprocate the ram, a second motor, a rotary shaft 25 driven by said second motor and provided with a pair of sprocket wheels arranged one at each side of said ram, and a pair of chains engaged one by each of said sprocket wheels and attached at their ends to said ram where- 30 by the ram may be moved upwardly to remove the cages from the vats.

10. In a pickling machine, the combination with a plurality of vats, of a verti-

cally movable ram provided with lateral arms having cages suspended therefrom, an 35 electric motor and driving connections therefrom to said ram for reciprocating the ram to cause the cages to move upwardly and downwardly in the vats, a second electric 40 motor, a pair of flexible members arranged one at each side of said ram and having their lower ends connected to the ram, and connections between said second motor and the upper ends of said flexible members whereby said ram may be raised and lowered 45 by the operation of the motor.

11. In a pickling machine a combination with a plurality of vats, of a vertically movable ram provided with lateral arms having cages suspended therefrom, means for reciprocating said ram to cause the cages to move upwardly and downwardly in the 50 vats, a motor, a pair of flexible members arranged one at each side of said ram and having their lower ends connected to the lower 55 portion of the ram, and connections between the upper ends of said flexible members and said motor whereby the operation of the motor is effective to move the ram upwardly to remove the cages from the vats. 60

In testimony whereof, I have hereunto set my hand.

WARREN C. LEINBACH.
